CABLE SPLICING DEVICE

William P. Montgomery, Allentown, Pa., assignor
of one-fourth to L. E. Curtis, Jr., and one-
fourth to John M. Harwick, Allentown, Pa.

Application July 2, 1932. Serial No. 620,699

2 Claims. (Cl. 140—119)

This invention relates to an improved and novel device expressly designed for effectively joining or splicing the ends of cables through the medium of a coupling sleeve.

5 At the present time cable ends are spliced by twisting the ends together in a burdensome and unsafe manner. Generally, the work requires the services of two men using special tools, one man holding the cable end with his tool and 10 the other man twisting the cables together with a similar tool. This is not only unhandy, but requires the men to work close together within the vicinity of highly electrified wires, thus making the job hazardous, time consuming, and otherwise unsafe and laborious.

The present invention relates to a unique and especially designed device usable by a single man and constructed for splicing the cable ends together through the medium of a coupling sleeve 20 which is twisted into place.

In carrying the invention into practice, I have discovered an unusual arrangement of parts carefully made and mechanically co-related to facilitate application and removal of the device, 25 as well as effective and dependable splicing of the cable.

The construction and relationship of the specific parts utilized for this purpose will become more readily apparent from the following description and drawings.

In the accompanying illustrative drawings wherein like reference characters are employed to designate like parts throughout the same:

Figure 1 is a top plan view of the device as 35 constructed in accordance with the principles of the present invention.

Figure 2 is a side elevational view thereof showing the manner of use.

Figure 3 is a front end view, that is, a view 40 observing Figure 1 in a direction from left to right with portions broken away to disclose the details.

Figure 4 is a transverse section taken approximately on the plane of the line 4—4 of Figure 1.

The preferred embodiment of the invention as disclosed in the drawings comprises a frame which includes a suitable gear casing or housing 5 formed on the front end of a base plate 6 which functions as a guide track. The numeral 7 merely designates a reinforcing web.

The casing is provided at its ends with closing plates 9 having suitable bearings for the end portions of a rotary shaft 10 (see Figure 3.) The shaft is provided with a worm 11 confined in the

casing and the terminals of the shaft are of polygonal construction as indicated at the points 12 to accommodate the removable hand crank or ratchet handle 13. This is applicable to either end for left-hand or right-hand use as desired. 60

A clamp 14 is formed as an integral part of the casing 5 and includes a fixed member 15 and a relatively movable member 16 hingedly connected as at 17 to the member 15. The end portions 18 are releasably joined together through 65 the medium of a pivoted screw-threaded stud 19 provided with a retaining thumb nut 20. These clamp sections or members are constructed to accommodate a special two-part gear, the parts of which are distinguished by the numerals 70 21 and 22 respectively.

The gear, as a unit, is formed with a central accommodation opening or hole 23. Moreover, the sections thereof are provided with grooves 24 into which retaining or set screws 25 project. 75 These set screws 25 are for the purpose of holding 21 in place when the part 16 is open.

The numeral 26 designates a longitudinally elongated malleable metal splicing sleeve, one end of which is adapted for connection with the rotary gear to rotate therewith, and the other end of which is adapted to be fixedly mounted on the frame. In order to secure the sleeve to the opening 23 in the gear, it will be observed that I provide interchangeable blocks or dies 27 which are 80 shaped to fit into said opening 23 and which themselves are shaped to conform to the splicing sleeve 26.

It will be noted that these die-blocks are held 90 in place and attached to the respective gear sections through the medium of set screws. Thus it is permissible to exchange the blocks to accommodate splicing sleeves of different cross sectional dimensions. As seen in Figure 3, the cable ends are distinguished by the numerals 28 and 95 29, the sleeves being fitted over said cable ends as shown in Figures 1 and 2.

The numeral 30 designates a slideable anchor for the opposite end of the sleeve 26 which comprises a pair of companion sections 31 and 32 100 respectively. These sections are hingedly connected together as indicated at 33 so that the section 31 functions as a jaw and the section 32 as a mounting. The latter section 32 is provided with L-shaped portions 34 which provide shoes slidably engaging the track plate 6. The numerals 35 and 36 designate rounded contact surfaces to facilitate sliding of the entire device 30 along the track or rail 6.

As seen in Figure 4, the complementary ends 31a 110

and 32a of the companion parts 31 and 32 are releasably joined together by a pivoted retaining stud 37 provided with a thumb nut 38.

It will be observed that the companion portions 31 and 32 have their adjacent faces notched or cut out to define a substantially square opening 39 into which the block-like retaining dies 40 fit. These dies correspond in function to the aforesaid dies 27 and are likewise held in place by set screws. This provides a convenient and satisfactory means for effectively attaching the adjacent end of the splicing sleeve to the slideable anchors 30.

Finally, I call attention to the numeral 41 which designates a retaining hook carried by the right hand end of the plate 6 to aid in positioning the device.

It is evident that by bringing the cable ends together in the relationship shown, and by placing the malleable splicing sleeve thereover, the splicing device may then be fastened in position. One end of the sleeve is releasably fastened to the gear sections 21 and 22 as seen in Figure 3, and the other end fastened likewise to the relatively adjustable sliding anchor 30. Thus, one end of the sleeve is fixed against rotation and the other end is allowed to rotate through the medium of the gear.

The rotary gear is turned by way of the worm 11 and the worm is actuated through the medium of the shaft 10 and ratchet handle 13. Consequently, by thus anchoring or holding one end of the sleeve and twisting the other end the cable ends 28 and 29 are spliced together in an obvious manner. The hinged section 16 of the gear housing or clamping means allows the dies 27 and sleeve 26 to be placed in position and removed.

Likewise, the hinged section 31 of the slideable anchor 30 serves in the same capacity.

The gist of the invention is in the provision of a frame including a base on which the slideable sleeve-anchoring means is mounted and adjustable toward and from the gear housing structure which is formed integral with the opposite end. The gear housing structure serves to accommodate the intermeshing gears and is made to facilitate application and removal of the device, as is the slideable anchoring means.

It is thought that the description taken in connection with the drawings will enable a clear

understanding of the invention to be had. Therefore a more lengthy description is thought unnecessary.

While the preferred embodiment of the invention has been shown and described, it is to be understood that minor changes coming within the field of invention claimed may be resorted to if desired.

I claim:

1. In a structure of the class described, in combination, a frame comprising a base plate, a gear housing at one end of the plate, a rotary shaft mounted in bearings in said housing, operating means for said shaft, a worm carried by the shaft, a centrally apertured sectional gear mounted for rotation in said casing and in mesh with said worm, said gear housing being provided with a hingedly mounted section carrying one section of said gear, the centrally apertured portion of the gear being such as to permit an adjacent end of a splicing sleeve to be releasably connected thereto, a slideable anchor on said frame, said anchor being apertured to permit the adjacent end of the sleeve to be attached thereto.

2. In a structure of the class described, in combination, a frame including a plate forming a horizontal track, a cable retaining hook at one end of the plate, a casing structure at the opposite end of the plate including a portion having bearings, a shaft mounted for rotation in said bearings, a detachable ratchet crank for operating the shaft, a worm keyed on the central portion of the shaft, a clamp comprising a relatively stationary section and a hinged section, a rotary split gear mounted for rotation in said clamp and having its teeth in mesh with the threads of said worm, one section of said split gear being carried by the hinged section of said clamp, said gear being centrally apertured to permit the adjacent end of a splicing sleeve to be detachably connected thereto for rotation therewith, and a slideable anchoring device on said plate movable toward and from the casing structure, and including a relatively stationary section and a companion hinged section, said sections being notched to form a central aperture to accommodate the adjacent end of the splicing sleeve.
